UNITED STATES PATENT OFFICE

2,554,410

RESILIENT STRIP JAR CAP WRENCH

John E. Herton, Los Angeles, Calif.

Application June 1, 1948, Serial No. 30,222

2 Claims. (Cl. 81—3.43)

1

This invention relates to new and useful improvements in wrenches especially adapted to remove screw-caps and like covers from jars, bottles or similar receptacles and to securely screw such caps or covers upon the receptacles for which they are intended.

An object of the present invention is to provide a simple nonmetallic wrench of the aforementioned character that is so designed as to be quickly and readily applied about a cap or cover to tightly grip the same, and which is applicable for caps and covers of various shapes or diameters.

Another object of the present invention is to provide a wrench for opening and closing the tops of jars and the like that is constructed of a steam, water, chemical and age resistant flexible rubber-like compound which incorporates a strip of strong and durable, flexible canvas of the same strength and high quality as that used in power belting, and which will be permanently molded into the back of the wrench so as to become an integral or unitary part thereof, thus adding great strength and preventing the breaking and splitting of the wrench, which often occurs to wrenches made of resilient or rubber material only. Such an inclusion of a reinforcing element of the foregoing characteristics, increases the durability and strength of the present wrench permitting the same to be used more effectively and efficiently for removing caps or covers from receptacles.

Another object of the present invention is to provide an all size flexible wrench which includes novel and improved finger engaging recesses on its outer face that are carefully and accurately spaced to receive the fingers of the user, thus enabling any number of the holes or recesses to be used as fulcrums and the fingers used as levers to provide an extremely powerful, non-slipping grip on any cover, so that it may be opened or closed frequently without damage to the cover, and the jars or receptacles can then be used indefinitely.

Heretofore resilient jar wrenches have been made of a continuous rounded section of a material having a predetermined size so that the same will be applicable for Mason type jars. When such wrenches are used for opening the caps or closures for many small receptacles, the wrench must be collapsed thus folding the sides of the wrench close together, unduly stressing the same and causing the same to break or split.

Accordingly, the present wrench has been designed to eliminate the foregoing undesirable oc-

2

currences by providing an endless or substantially endless wrench since the elongated strip forming the same is provided with eyelets at its ends into which is incorporated a free running metal ring to allow for instant zero contraction, thus the ends of the wrench can be brought very closely together any number of times with no stress whatever on the wrench itself.

A further object of the present invention is to provide a flexible wrench that is small and compact in structure, strong and reliable in use, neat and attractive in appearance, economical to manufacture, and otherwise carefully designed and well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the present invention, and with parts thereof broken away and shown in sections for the purpose of illustration, and showing in dotted lines the said wrench applied to a jar cover of medium size;

Figure 2 is a longitudinal sectional view of the present invention taken substantially on the plane of section line 2—2 of Figure 1; and,

Figure 3 is a fragmentary plan view of the present invention showing the holding ring removed therefrom.

Referring now to the drawings in detail, wherein for the purpose of illustration, there is disclosed a preferred embodiment of the present invention, the numeral 10 represents an elongated, substantially rectangular strip of flexible steam water, chemical and age resistant rubber-like material that is sectioned or cut from a length or roll of such material to reduce to a minimum the amount of material wasted during the construction or manufacture of the present invention.

Fixed to the outer face of strip 10 and pressure molded into strip 10, so as to become a permanent integral part thereof, is an elongated backing 12 of very strong, durable, flexible canvas that will reinforce the strip 10 to give durability thereto and which will prevent the latter from breaking, splitting or tearing in use. This backing 12 is provided with a plurality of longitudinally spaced finger receiving openings 14 that oppose concave recesses 16 provided in the outer face of strip 10.

Integrally formed with the inner face of the strip 10 is a plurality of longitudinally spaced,

transversely extending parallel gripping teeth or ribs 18 for engaging the outer surface of a jar cover, cap or the like 20.

The ends 22 and 24 of the strip 10 and backing 12, are respectively provided with openings 26 that fixedly engage reinforcing sleeves 28 that slidably receive a holding ring 30. This holding ring 30 is employed for retaining the ends of the strip 10 and the backing 12 relative to each other so that the present wrench will be substantially in the form of a loop or continuous band, as shown best in Figure 1 of the drawings.

In practical use of the present invention, the same is slipped over the top 20 so that the teeth 18 will engage the outer circumference of the top or cover 20. A user grips the body portions of the present invention in one hand and inserts his fingers into the appropriate openings 14 and recesses 16, whereby the top may be rotated or turned to be applied to or removed from a bottle, jar or the like.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A universal wrench for removing and replacing tops and covers of receptacles by hand pressure comprising a strip of resilient material having a toothed inner surface, a heavy flexible canvas backing permanently embedded in the

outer surface of the strip, a plurality of longitudinally spaced openings in said backing, a plurality of finger receiving recesses provided in the outer surface of the strip registering with the openings in said backing, metal eyelets permanently embedded at the ends of said strip, and a strong metal ring free running through the eyelets to provide the means for connecting the ends of the strip to each other, and to allow for instant zero contraction or instant maximum expansion of said wrench.

2. A device for removing or replacing tops on receptacles comprising a strip of resilient material having a toothed inner surface, a flexible backing fixed to the outer surface of the strip, a plurality of longitudinally spaced openings provided in said backing, a plurality of finger receiving recesses provided in the outer surface of the strip registering with the openings in said backing, and means for connecting the ends of the strip to each other.
